LEMMA J. ROOT, OF SEATTLE, WASHINGTON.

GASOLINE ENGINE.

Application filed September 26, 1923. Serial No. 665,012.

The invention is an engine in which the size of the explosion or compression chambers of the cylinders is automatically adjustable, in which the valves have a free opening and will not need re-grinding, in which the engine is automatically cooled by air currents, in which the piston rings are non-leakable, and in which there is a positive oiling system.

10 The object of the invention is to provide an engine in which the entire explosive chamber is directly above the piston which brings the full force of the explosion directly on the piston.

15 Another object of the invention is to provide an engine in which the size of the explosive or compression chamber is automatically adjustable so that a small amount of explosive mixture will be compressed to the same density as a larger amount, thus giving proper compression and full efficiency to each charge.

20 A further object of the invention is to provide an engine whose cooling system can be adjusted to automatically cool the engine to any desired temperature.

25 A still further object of the invention is to provide an engine whose piston rings will reduce the leakage between the cylinder wall and the piston to a minimum.

30 And a still further object of the invention is to provide an engine whose valves have a free and large opening and will not warp or need re-grinding and with a positive oiling system.

35 With these and other ends in view the invention embodies an engine in which the upper ends of the cylinders will move automatically to change the size of the explosion chamber, with valves, a fan, arranged in suitable air passages so that warm or cool, air may be forced into a jacket surrounding the engine, and piston rings with grooves in their interior surfaces.

40 Other features and advantages of the invention will be seen from the following description taken in connection with the drawings, wherein:

Figure 1 is a side elevation of an engine 50 with some parts omitted and others broken away.

Figure 2 is a plan with parts omitted.

Figure 3 is a plan view of the valve gears.

Figure 4 is a detail showing an alternate 55 design with sleeves for engaging the lower

ends of the cylinders as the walls of the cylinders move upward and downward.

Figure 5 is a sectional view looking toward the front end of the engine.

Figure 6 is a cross section through the center-line of one of the cylinders.

Figure 7 is a plan view showing one of the valve operating gears.

Figure 8 is a view of the under side of the gears shown in Figure 7.

Figure 9 is a sectional detail showing the piston ring.

In the drawings I have shown my engine as it would be constructed wherein numeral 1 indicates the movable head, numeral 2 the 70 fan, and numeral 3 the piston ring.

The head 1 can be constructed as shown with a rectangular shaped block 4 having passages 5 and 6 therein which extend downward into cylindrical shaped projections 7 75 which fit in the upper ends of cylinders 8. The cylinders may be of any suitable type or size with the upper ends open as shown in Figure 5 or with the cylinder walls 9 made integral with the head 1 so that the entire 80 cylinder may raise in relation to the piston. The engine block may be provided with flanges or sleeves as shown in Figure 4 and should the cylinder walls be made integral with the head in order to secure the required weight above the pistons. Spark-plugs 10 may be placed in offset portions 11 in the sides of the cylinder wall and arranged so that their tips will project into the cylinder at points below the lower position of the movable head. The passages 5 and 6 may be connected to inlet and exhaust manifolds 12 and 13 which may be of any suitable type or design and the exhaust manifold should have a flexible section 14 95 in it as shown in Figure 1. The intake manifold may be of any suitable design and may have any type of carburetor as indicated by the numeral 15 attached to an extension 16 and the carburetor may have a 100 supply pipe 17 with a flexible section in it as indicated by the numeral 18.

The projections 7 may be of any suitable length and may be provided with piston rings 19 in their outer walls so that the mixture will not escape out of the upper ends of the cylinders. These projections have passages 20 and 21 in them which connect to the passages 5 and 6 and in their lower ends are openings 22 and 23 as shown in 110

Figures 6 and 2. Below the openings 22 and 23 are the valves 24 which are in the form of discs with convex upper and lower surfaces as shown in Figure 6 and an opening through them as indicated by the numeral 25 shown in Figure 2. The valves have vertical stems 26 projecting upward through holes 27 and on the upper ends of the stem are discs 28 with springs 29 below them which hold the valves upward against the lower concaved surface of the projection 7. Gears 30 are fixedly mounted on the valve stems for operating the valves. These gears are made and operated as shown in Figures 7 and 8 and are rotated by segmental gears 31 on shafts 32 which are rotated by worm gears 33 on a shaft 34 and these shafts are rotated by the crank shaft through a spur gear 35, worm gears 36 on a shaft 37 and other worm gears 38 between the shaft 37 and the shaft 34. The gear 35 is rotated by a gear 39 which also rotates a pump gear 40 which operates a pump 41 shown in Figure 1, which may be of any suitable design. The pump 41 has a pipe 42 connecting it to the bottom of the crank case and a discharge pipe 43 which has suitable branches in it to connect it to points 44, 45, and 46, adjacent the bearings of the crankshaft, also to suitable points so that it will spray oil on the connecting rod bearings, and also to a point 47 which may be at any convenient point in the casing 48 in which the valve gears are mounted on top of the cylinder head 1. This latter connection will have a flexible section 49 in it so that the cylinder head can move upward and downward. The oil will pass from the casing 48 back to the crankcase by flowing down the sleeve surrounding the vertical rod 37.

The cylinder head 1 has pins 50 at each end upon which levers 51 are pivotally mounted which hold the cylinder head downward through an eccentric 52 and a spring 53 which is connected to the eccentric by an arm 54. The eccentric is pivotally mounted on a pin 55 on the frame and arranged in such a manner that as the pressure in the cylinders reaches a pre-determined degree the spring 53 will permit the arm 54 to move downward so that the cylinder heads may move upward, thereby permitting the pressure in the cylinders to remain constant. It will be seen that this pressure may be regulated by adding additional weight to the head 1 or by adjusting a nut 56 on the spring stem 57 and as the eccentrics at each end are connected by a rod 58 in hubs 59 on the arms 54, the heads of all of the cylinders will move upward and downward simultaneously. It will, therefore, be seen that it will be possible to compress a light charge of fuel to as great a pressure as a heavy charge as the size of the compression

chamber will be automatically adjusted to a small area for the light charge and automatically increased by the compression and the explosion of the larger charge to a larger area for the heavy charge. This area may also be regulated from the instrument board by moving a rod 60 backward and forward which will extend from the arm 54 to a suitable means at the instrument board for holding it in different positions. The springs will normally be set to hold the piston heads downward until a pressure, greater than that which may have been determined as the most efficient pressure to explode the gas, is reached and then the springs will compress and permit the heads to raise as much as may be necessary to provide a suitable area for the heavier charge.

The valve gear 30 is made in the form of a disc with teeth around its edge and projections 61 at intervals in the teeth. Below the teeth are wings 62 which are separated from the teeth by a small space in which the outer edge 63 of the gear 31 will extend. The gear 31 may be made as shown in Figures 6 and 7 with lugs 64 having teeth 65 on the upper side of its outer edge, which lugs will engage the projection 61 on the gear 30 and which teeth will engage the teeth 60 of the gear 31. The under side of the gear 31 is provided with circular openings 66 and 67 as shown in Figure 8 in which the points of the wings 62 may project as the lugs 64 and wings 62 are rotating the gear 30. The gears 30 and 31 are provided with square holes 68 and 69 through which they are mounted on the square sections of the shafts 32 and on the valve stems. It will be seen that as the gear 31 rotates one of the lugs 64 will engage one of the projections 61 and the tip of one of the wings 62 will engage the edge of one of the openings 66 and cause the gear 30 to rotate and as it continues to rotate the tip of the adjacent wing 62 will pass into the opening 67; and as soon as the lug 64 has passed by the gear 30 a surface 70 of one of the wings 62 will engage the outer surface 71 of the lower part of the gear 31 and hold the gear 30 in the rigid position until another of the lugs 64 engages one of the projections 61. In the design shown the gears are set to rotate the valves so that the opening 25 will pass over the closed portion of the projection 7 while the fuel is being exploded and then it will first open the exhaust port 23 to permit the exhaust to escape and then close the exhaust port and open the intake port 22 so that fuel may be admitted to the cylinder, thus closing through the other full stroke of crank as gear 31 rotates one half as fast as crank shaft.

It will be seen that the valves may be set to correspond with the timing gear so that fuel may be admitted and the exhaust gases

discharged at any desired interval. It will also be seen that the worm gear 38 may be provided with a square hole 72 so that it may be mounted on the square section at the upper end of the shaft 37 so that it may slide upward and downward on the shaft as the cylinder head moves upward and downward.

One of the shafts 32 may be provided with an extension 74 that will extend through an opening 75 in the cover of the gear case 48 so that a timer as indicated by the numeral 76 may be placed upon it; as the gear 31 rotates at the proper speed for the timing gear. The timer may be of any suitable design and may be connected to the sparkplugs of the engine in any suitable manner.

The fan 2 may be rotatably mounted in a casing 77 on a shaft 78 and driven by a belt 79 from a pulley 80, or any suitable means from the crankshaft. The casing 77 is arranged so that the air may be drawn through a device 81 which may be similar to a motor vehicle radiator and from there it may pass backward to tubes 82 and 83 which may have openings 84 in their outer edges through which the air may be blown against the interior walls of a casing 85 which may be placed around the engine. The air will circulate upward along the interior of the casing and then downward around the engine from where it may escape or may be drawn forward through a passage 86 to the fan so that in very cold weather the air may be re-circulated. A damper 87 may be placed in this passage which may be regulated by a rod 88 from the instrument board; or it is also understood that this damper may be regulated by a thermostat on the side of the engine as indicated in dotted lines as shown in Figure 1. A bar of thermostatic material 89 may be attached to a block 90 at one end and to the bar 88 at the other so that as the temperature of the bar is changed it will move backward and forward and regulate the temperature by operating a gate or damper between the two air passes. The element may be enclosed in any suitable casing and arranged in any suitable position on the engine where it will be affected by the temperature of the engine. It will be seen that this will make it possible to automatically distribute the air over the entire engine at practically an even temperature.

The piston ring 3 which may be as shown or of any suitable type is provided with a groove 91 as shown, or being shaped of any

angle, around its inner surface so that a lining of asbestos or the like which is indicated by the numeral 92 and which may be placed behind the piston ring, may be squeezed into the groove 91 so that it will be practically impossible for anything to pass around behind the ring. Thus making a piston ring that will seal a passage that may exist between a piston and the ring. It is understood that this groove may be placed in a ring of any design.

It will be understood that changes may be made in the construction without departing from the spirit of the invention.

Having thus fully described the invention, what I claim, is:—

1. In an internal combustion engine, a plurality of cylinders forming a group, a plurality of movable heads mounted in a common block, arms pivotally attached to the ends of the block, eccentrics at the lower ends of the arms for regulating the positions of the heads in the cylinders, levers connected to the eccentric and to springs for regulating the positions of the eccentric, means for regulating the positions of the eccentrics from a remote point, valves in the said heads of the cylinders, means for operating the said valves as the said heads move upward and downward, inlet and exhaust manifolds connected to the said movable heads, flexible means connecting the exhaust to the exhaust pipe, and flexible means connecting the carburetor of the intake ports to the gasoline supply line.

2. In an internal combustion engine a plurality of cylinders forming a group, a plurality of movable heads mounted in a common block, arms pivotally attached to the ends of the block, eccentrics at the lower ends of the arms for regulating the positions of the heads in the cylinders, levers connected to the eccentric and to springs for regulating the positions of the eccentric, means for regulating the positions of the eccentrics from a remote point, valves in the said heads of the cylinders, means for operating the said valves as the said heads move upward and downward, inlet and exhaust manifolds connected to the said movable heads, flexible means connecting the exhaust manifold to the exhaust pipe, flexible means connecting the carburetor of the intake ports to the gasoline supply line, and a flexible oil connection for supplying oil to the said valve operating means.

LEMMA J. ROOT.
